UNITED STATES PATENT OFFICE.

WILLIAM J. NEIDIG, OF MADISON, WISCONSIN, ASSIGNOR TO NEIDIG TYPEWRITER CO.,
OF CHICAGO, ILLINOIS, A CORPORATION OF ILLINOIS.

TYPE-WRITING MACHINE.

1,113,572.

Specification of Letters Patent.

Patented Oct. 13, 1914.

Application filed December 5, 1912. Serial No. 735,108.

To all whom it may concern:

Be it known that I, WILLIAM J. NEIDIG, a citizen of the United States, residing at Madison, in the county of Dane, State of Wisconsin, have invented a certain new and useful Improvement in Type-Writing Machines, of which the following is a specification, reference being had therein to the accompanying drawings.

10 Certain principles and features of my invention as described herein are included within the generic invention which is described and claimed in Letters Patent No. 1,053,919, granted Feb. 18, 1913, upon my 15 co-pending application filed April 20, 1908, Serial No. 428,212.

One of the objects of my general invention is to supply the operator of a typewriting machine with means, controlled by the sheet 20 upon which he is writing, for indicating progressively the position of his sheet.

Other objects are to supply him with improved sheet-controlled means whereby such types as may be desired of visual, audible 25 and machine-lock signaling devices may be employed to indicate the arrival of the sheet into predetermined position.

The present branch or division of my invention has as one of its special features a 30 novel use of the leading end of the sheet for the control of indicating means.

In the embodiments of the invention represented in the drawings, the types of indicating means shown as so controlled by the 35 leading end of the sheet comprise indices, a visual signaling means, an audible signaling means, and a means for locking the printing instrumentalities against use in printing.

Another special feature of the present 40 branch of my invention is the combination of a friction-drive device for the central operative member with actuating devices of a positive type, or more specifically as illustrated herein of the toothed gear type, combining the responsiveness to control of a frictional actuation with the positiveness of a toothed actuation.

Still another special feature is the use of an auxiliary or intermediate controlling 50 mechanism between the sheet and the operative member, most of the work of actuating the devices for controlling the operative member being done under the control of the sheet by one of the typewriter parts, namely 55 in the present case the platen, instead of by

the sheet directly, and the action of said devices being delayed to any extent desired.

Another special feature is the use of a typewriter part for retracting the paper-feeler from sheet-controlled position, the retraction in the present embodiments being represented as accomplished by the forwardly moving platen through the instrumentality of a cam.

Another special feature is the use of a 60 novel form of detent constructed to restrain the member detained from movement in either direction.

Other features are as will be described hereinafter.

The said special features are intended for use as may be found desirable in connection with sheet-position-indicating mechanisms under the varying conditions of service.

In the drawings.—Figure 1 is an end elevation of portions of a typewriting machine showing my invention as applied thereto, the structure being partly broken away and shown in section on the three lines 1—1, Fig. 3. Fig. 2 is a plan view of portions of the same. Fig. 3 is an enlarged cross-section on the line 3—3, Fig. 1. Fig. 4 represents a modified detail. Fig. 5 represents portions of Fig. 1 modified by the omission of certain elements. Figs. 6 and 7 represent typical alternative arrangements of indices. Fig. 8 is an end elevation of portions of a typewriter carriage showing, partly broken away and in section, a typical embodiment of my invention having certain details modified in form and position. Fig. 9 is a plan view, partly broken away and in section, of an embodiment of my invention as applied to the other end of the platen and having the control thereof in the space-lever instead of the sheet. Fig. 10 is an end elevation, and Fig. 11 a cross-section thereof on the line 11—11, illustrative of another embodiment of my invention, showing control by the bottom end of the sheet instead of the leading end and the drive being differently geared. Fig. 12 represents the indices preferably used with the device shown in Figs. 10 and 11.

The main frame of a typewriting machine 10 is indicated at 1 (Fig. 1), mounted upon which is the usual transversely movable carriage-frame 2 bearing paper-table 3. The usual platen for advancing the sheet is indicated at 4 fixedly attached upon its arbor 5 11

journaled in the ends of said carriage-frame, said platen being rotated by usual line-space mechanism as in practice. Usual type-bars indicated at 7 and bearing printing types 8 are mounted on the main frame so as to move about their axes 9 under the actuation of key-levers 10, all in well-known manner. The remaining typewriter parts are or may be as in practice.

10 As applied to the above structure, the embodiment of my invention more particularly illustrated in Figs. 1 to 3 is described as follows: Platen 4, platen-arbor 5 and platen-head 11 are connected in convenient manner to rotate in unison, as usual. Attached at the end of the platen to rotate therewith is a toothed rim 12, against which may be placed a friction-washer 13 of leather or the like, although the washer is not essential. Journaled loosely upon platen-head 11 is operative member 6, in this case having the form of a revoluble composite drum or index-carrier. Said member is given frictional actuation from the platen by convenient means, preferably by being spring-pressed laterally against the end of the platen, and it receives positive actuation from the platen, preferably through toothed gearing contained within the drum contour 30 one wheel of which is mutilated. The position of the mutilated wheel in the gear train, in case such a wheel is used, is not especially material, nor is the character of the gear train.

35 In the illustrated embodiment toothed wheel or driver 16, conveniently rotated from the platen arbor by means of key 17, has journaled upon the hub or collar portion thereof a laterally acting dished spring 40 pressed centrally by said toothed wheel against an instanding portion 6' of said operative member, said wheel in turn being conveniently maintained in lateral position by shouldered sleeve 19 fixedly attached in 45 carriage-frame 2, a downstanding pin or key 20 on piece 21 conveniently serving to maintain said sleeve in fixed angular position. Fixedly attached upon said sleeve by the central or web portion thereof is toothed wheel 22, said wheel having internal teeth and having some of said teeth removed at 23 (Fig. 1), that is to say being a stationary mutilated wheel. Fixedly attached upon the instanding portion 6' of operative 50 member 6 aforesaid is pin 24, journaled upon which so as to mesh with wheels 16 and 22 is toothed wheel 25. Said wheel is a planet wheel, rotating about the axis of its driver as well as about its own axis. Planetary action is not essential, but the arrangement shown is as convenient and simple as any known to me. Member 6 has a laterally extending annular portion 26 constructed having a detent-recess 14 (Fig. 1). 60 A cam-slope 27 leads from the lip of said

recess to the peripheral arch of said annular portion or annulus 26, one of the functions of said annulus being that of a cam, as will be hereinafter explained. Means for adjusting or changing the angular position 70 of the main portion of member 6 relatively to said annulus and its detent-recess 14 are shown, one thereof being movable upon the other and bolts 29 (Figs. 2, 3) passing through the overlapping portions and holding the parts in fixed relation when tightened, one of said portions being supplied with circumferential slots 30 for said bolts.

With reference to the parts in control of said structure,—an upstanding extension of 80 carriage-frame 2 (Fig. 1) bears a laterally extending pin or rod 31 for the convenient attachment of paper-support 32. Said paper-support is preferably slightly dished, for the better reinforcement of the sheet 85 under thrusting action, and it is supplied with a slot or opening 33. The same frame-extension bears also a laterally extending shouldered axle 34, journaled end to end upon which are two sleeves, the inward one, 90 indicated at 35, Fig. 2, having fixedly attached thereon a paper-feeler 28 adapted to enter slot 33. Paper-feeler 28 is in control of an auxiliary or intermediate device for controlling the movement of member 6, said device in this embodiment including a toothed segment having a constant starting position and actuated through teeth from the platen, and the controlling means acted upon being in this embodiment a stop or detent. Fixedly 10 attached upon sleeve 35 near the outward end thereof is an arm 36 bearing a laterally extending pin 37, on which is journaled a part 38 having a downwardly extending segmental portion supplied in this 10 case with a single tooth 39, said tooth being adapted to enter the interdental spaces in toothed rim 12 above referred to. Said part 38 also has an upwardly extending portion bearing an outwardly extending pin 11 40 and an inwardly extending pin 41, the latter being adapted to engage upon a lug 41' on arm 36. The parts on sleeve 35 are preferably so closely balanced that paper-feeler 28 barely tends to enter slot 33, conveniently if needed by the addition of an eccentric weight 42 attached on said sleeve. The outward sleeve on axle 34, indicated at 12 43, bears fixedly attached thereon a stop 15 having an arm 44 supplied with a slot 12 45 into which pin 40 on part 38 projects. Said stop 15 has a two-fold function: First, it is adapted to enter detent-recess 14 and detain member 6 in initial position from movement in either direction. One of the 12 walls of said detent-recess is made radially higher than the other in order that said stop may not fail to engage thereon whatever the speed of forward actuation of member 6. The recess provision with two detaining 13

walls is adapted to detain said member in initial position under irregular actuation thereof, as in backward removal of the sheet, or, in the case of certain embodiments to be described herein later, in the preliminary positioning of the sheet. The second function of stop 15 is to serve as a cam-follower for moving the paper-feeler away from sheet-controlled position through cam-slope 27 hereinbefore referred to, under the actuation of the platen. It will be understood that the sheet receives usual support and guidance from feed-rolls and feed-guides adjacent the position of the paper-feeler as described, so that the leading end even of the thinnest paper is able to actuate such a lightly poised paper-feeler out of its slot without danger of buckling. This portion of the mechanism operates as follows: The paper-sheet 46 is entered in usual manner down paper-table 3 and advanced by the platen into position for printing. Preferably just before it attains such position the leading end of the sheet encounters paper-feeler 28 and raises it from slot 33 in paper-support 32, thereby rocking sleeve 35 and lowering arm 36 so that tooth 39 enters an interdigital space of toothed rim 12. Said toothed rim is moving with the platen; it at once acts on said tooth, moving part 38 about its axis 37 and pin 40 downwardly in slot 45 in the rear portion 44 of stop 15, thereby causing said rear portion to be depressed and stop 15 lifted out of recess 14. By this time tooth 39 has been actuated entirely out of the path of the teeth on rim 12. This action has also brought pin 41 on part 38 in contact with lug 41' on arm 36.

It will be understood that member 6 has previously been detained by stop 15 in initial position as shown in Fig. 1, with toothed wheel 25 maintained out of mesh opposite the mutilated portion 23 of toothed wheel 22. Member 6, no longer detained by stop 15 and having frictional actuation from the platen induced by the pressure of spring 18, is now rotated frictionally by the platen until the teeth of wheel 25 are carried into mesh with those of stationary wheel 22, after which it has toothed actuation from the platen. It will be understood that the speed of member 6 relatively to that of the platen can be as desired when the toothed wheels are in mesh: By the arrangement of gearing shown in Fig. 1 the speed is retarded. Meanwhile cam-slope 27 has acted to change still further the position of stop 15, thereby through pin 40, pin 41, lug 41', and arm 36 rocking the sleeve 35 and causing paper-feeler 28 to be lifted quite away from the sheet. Tooth 39 by the same action is lifted quite away from toothed rim 12. During the remaining progress of the sheet the said retracted parts are maintained out of en-

gagement with said sheet and toothed rim by annulus 26.

As member 6 is always in the same rotative position when released from the control of stop 15, and is released always with the arrival of the leading end of the sheet into a definite position, and thereafter is advanced by the same agent that advances the sheet, namely the platen, coördinately with the sheet, its working position is always related to that of the leading end of the sheet. It can therefore be supplied with indices to indicate the various positions of the sheet. The indication may be in any unit desired, beginning where desired and ending as desired. I prefer to use indices of familiar character involving no mental calculation or memorizing, such as the ascending series of numerals shown in Fig. 2, or the downward-counting numerals shown in Fig. 6. Where desired, indices in a series extending through a plurality of revolutions of member 6 may be employed, as shown in Fig. 7, without change of any kind in the mechanism, stop 15 being held from entering recess 14 during the presence of a sheet over slot 33. That is to say, an index 1 may be brought into indicating position when the sheet is in position for printing the first line, and index 2 for the second line position, and so on for any length of sheet. I prefer to gear down member 6 so that its indicating functions will be completed with a single revolution thereof. I use for a stationary index to coöperate with member 6 a shield-pointer 74 attached to carriage-frame 2, said index constructed to shield member 6 from view except at indicating position and above, so as to be able to employ with greater effectiveness a visual signaling agent on said member, said agent preferably being adjustably added upon the index periphery of the member. A small circle of gummed colored paper or the like, indicated at 6^b, forms as convenient a signaling agent as any. Said circle is concealed from view by the shield-pointer, but at the predetermined sheet-position comes into view from behind said pointer. The indicating portion of member 6 is adjustable relatively to detent-recess 14 as before described for two leading purposes, first to adjust the indices so that they will indicate if desired the number of the line-position relatively to the first line-position, which may fall at one distance or another from the leading end of the sheet, and second, to adjust by mechanical means if desired the time of operation of said visual signal. The provision can also be used to adjust the time of action of the additional indicating means now to be described.

The additional indicating means are to be employed at will as follows: The face-wall of member 6 is supplied with a series of threaded holes or seats 47', into any one of

which the threaded shouldered pin 47 may be screwed, said pin being thereby angularly adjustable on said member. Laterally extending pin 48 on carriage frame 2 has journaled thereon an elbow-lever 49, one arm of which projects into the path of said pin 47 and the other arm of which bears pin 50. Carriage frame 2 bears also the laterally extending pin 51, journaled upon which is rocking piece 52, a similar pin 51 being carried upon the inner end of said carriage frame directly behind the portion shown, journaled upon which is a similar rocking piece 52, as will be understood. The said rocking pieces 52 are connected by a laterally extending bail portion 53 and form with it a rocking bail-piece or universal connection between the carriage and the main frame portions of the mechanism. Said bail-piece is connected with lever 49 by means of rod 54, journaled at one end on pin 50 before mentioned, and having an elbow-slot 54' at the other end, into which projects pin 55 on piece 52. Main frame 1 has journaled thereon in the ends of transversely extending rock-shaft 56, said shaft having a lever-arm 57 fixedly attached thereon about midway between the end thereof in suitable position to be engaged by bail 53 in every working position of the carriage. Arm 58, also fixedly attached upon said rock-shaft, bears pin 59, journaled upon which is one end of downwardly extending rod 60. Main frame 1 has also journaled therein the ends of a rock-shaft 61 having fixedly attached near either end the arms 62, said arms being connected by a transversely extending bail-rod 63. One of said arms bears a pin 64 upon which the lower end of rod 60 is journaled. Rock-shaft 61 has fixedly attached thereon a hub 65, preferably angularly adjustable with respect thereto by means of a set-screw 66. From said hub extends the light spring shaft 67 bearing bell-hammer 68. Bell 69 is conveniently supported in the path of said hammer by central pin 70 on frame 1. The usual key-levers 10 are supplied each with the overhang 10' in such manner that bail-rod 63 can be moved under them to lock 50 them against actuation, but when said bail-rod is in the position shown in Fig. 1 they are not locked thereby. A spring 72 attached at one end to one portion of arm 58 and at the other end to laterally extending post 71 on frame 1 tends to hold arm 57 against laterally extending cross-portion 73 of frame 1 and bail-rod 63 out of locking position.

The mechanism described operates as follows: At the predetermined time pin 47 engages elbow-lever 49, rocking bail 53 downwardly against lever 57, thereby through the connecting parts rocking shaft 61 so that hammer 68 strikes bell 69 and bail 63 passes under key-lever overhang 10'. The operator

is made aware through the audible signal that he has printed his predetermined last line, and without wasting time to test the key-levers is able to remove his sheet at once. If he neglects to notice the audible signal he finds the key-levers locked so that he can do no more printing. In case he wishes to print further upon that sheet he can do so by lifting elbow-slot 54' upward on pin 55, whereupon spring 72 is enabled to restore the parts into inoperative position, pin 55 passing into the horizontal portion of said elbow-slot and permitting the movement. In case he removes his sheet without printing further thereon, pin 47 merely actuates lever 49 out of its path until the parts clear, whereupon the parts resume their position of Fig. 1 by gravity and the action of spring 72.

It will be understood that member 6 is detained in starting position by stop 15 ordinarily during the preliminary progress of the sheet into printing position, usually about three-quarters of a revolution of the platen being required to position the sheet. The movement of the platen employed in removing the completed sheet, or part of it, is also available for use in rotating recess 14 into engagement with said stop between the completion of one sheet and the beginning of the next.

An alternative form of part 38 of Fig. 1 is represented at 38' in Fig. 4, the segment 39' in this case being a friction-segment instead of a toothed, and the actuation by the platen being a frictional actuation instead of through teeth. Its action is the same, pin 41 co-operating with slot 45 as before, and the platen acting through said friction-segment 39' to lift stop 15 out of detent-recess 14.

In many cases a mechanism of the slippage of action described will not be required, the leading end of an ordinary sheet having sufficient power to control the action of member 6 without the aid of the platen or other intermediate agent.

Fig. 5 represents the sheet-controlled portions of the mechanism with the intermediate controlling device removed. Paper-feeler 28 and stop 15 are as before described, but both are fixedly attached upon the same sleeve 43' journaled on axle 34, and the leading end of the sheet acts directly to lift stop 15 out of detent-recess 14. Cam 27 then acts upon the stop and retracts the paper-feeler from contact with the sheet.

Fig. 8 is a representation of another embodiment of my invention, showing differences in the manner of applying the same. An upstanding and outstanding portion of carriage frame 2' bears inwardly extending axle 34', upon which is journaled sleeve 35'. Said sleeve bears fixedly attached thereon a paper-feeler 28', an arm 36', and a stop 15', and it bears loosely journaled thereon be-

tween said arm and said paper-feeler a super-sleeve 43^a upon which adjacent to said arm is fixedly attached a stop 15^a. Paper-feeler 28^a has a path into a slot in paper-table 3 indicated at 33^a. Stop 15^a is adapted 5 to enter detent-recess 14 on member 6 as hereinbefore described. An arm 36^a bears an inwardly projecting pin 41^a adapted to engage upon said stop 15^a liftingly. Other 10 parts are as follows: On platen arbor 5 outside of frame 2^a is placed a washer 19^a for pressing centrally upon a laterally acting dished spring 18^a, said spring lying within the contour of a cam 38^a journaled on the 15 platen arbor and acting to press said cam laterally into frictional engagement with the laterally extending annular driving portion 12^a of platen twirler 4^a, fixedly attached as usual to rotate with the platen. Cam 38^a 20 contains a detent-recess 14^a having two walls one preferably higher than the other as described in connection with detent-recess 14, and it bears a working cam-slope 27^a. Stop 15^a is adapted to enter said detent-recess 25 and detain said cam against movement in either direction. Stop 15^a is also adapted to cooperate with cam-slope 27^a as a cam-follower, said cam-slope taking the place of cam-slope 27 on annulus 26 before described. 30 (Fig. 1). The indicating mechanism is as shown in Figs. 1 to 3, before described.

The embodiment acts as follows: Cam 38^a has been detained in constant position by the action of stop 15^a on recess-detent 14^a during 35 removal of the preceding sheet, or prior thereto. Member 6 is also shown in constant starting position, under the control of stop 15^a, although it may be positioned somewhat later. Sheet 46 is placed on paper-table 3 in usual manner, the leading end being positioned into the angle between feed-roll 4^a and the platen as usual, ready for entrance into the machine, said leading end while being so positioned moving paper-feeler 28^a out of slot 33^a, thereby rocking sleeve 43^a and lifting stop 15^a out of detent-recess 14^a. That is to say, the leading end 45 of the sheet after having acted controllingly upon said paper-feeler is given a position definitely related thereto, where it awaits the action of the paper-feed mechanism, at the same time that cam 38^a in its constant starting position awaits actuation from the same paper-feed mechanism. The platen is 50 now rotated, cam 38^a under its frictional actuation rotates therewith, and the sheet is advanced toward printing position. Continued rotation of the platen brings cam-slope 27^a in engagement with stop 15^a, raises 55 said stop, rocks sleeve 43^a and arm 36^a, and through pin 41^a lifts stop 15^a out of detent-recess 14^a, whereupon the released member 6 under its frictional and toothed actuation 60 brings (say) index 1 into indicating position 65 as before, to indicate (say) the first line

position on the sheet. Thereafter during the remaining progress of the sheet operative member 6 moves in coördination with the sheet and the indices thereon are brought into indicating position as before described. 7 One of the prominent functions of the intermediate cor'rolling mechanism in this case is to delay the calling of member 6 into action during the preliminary positioning of the sheet. It will be noted that the control of stop 15^a by the leading end of the sheet occurs while the platen is at rest, the only work required of the sheet being the lifting of said stop and paper-feeler, which may be constructed as light as desired. 8

Fig. 9 represents another embodiment. Operative member 6 for convenience is here shown as mounted at the right-hand end of the platen, outside of the carriage-frame. The construction of the indicating mechanism is the same as that shown in Figs. 1 to 3, except annulus 26 bearing detent-recess 14 for convenience becomes annulus 26^b on the left-hand side of member 6, and the frictional actuation from the platen is given by laterally extending portion 12^b of platen twirler 4^b in coöperation with instanding portion 6^b of said member, said twirler being attached in usual manner upon the platen arbor to rotate in unison with the platen. The control of the mechanism, however, instead of being by the sheet, is by the line-space-lever 46^b, which is conveniently supplied with a slide portion 40^b adapted to engage at the beginning of each actuation of said line-space-lever upon a cam-surface 45^b on the rear portion of stop 15^b. Member 6 is brought into starting position during the removal of one sheet and positioning of the next through the detaining action of stop 15^b upon detent-recess 14, said recess securely detaining the member under the usual irregular backward and forward positioning movements of the platen. The index in indicating position during said detention may conveniently be index 1. The first line is written and line-space-lever 46^b grasped as usual by the operator to advance the sheet into the next line-position. The first action of the line-space-lever is to depress cam 45^b, thereby raising stop 15^b out of detent-recess 14 and releasing member 6 to be actuated at first frictionally and then through teeth from the platen, which is advanced as usual by the latter portion of the spacing stroke. At the end of the advance movement the sheet will be in (say) the second line position, and member 6 will have brought (say) index 2 into indicating position. Thereafter member 6 will move coördinately with the platen and through it will be called into operation the several indicating devices previously described herein.

Figs. 10, 11 and 12 represent an embodiment controlled by the bottom end of the

sheet, instead of the leading end, and also show the operative member as geared up by convenient means to move faster than the platen for reasons that will appear. Member 6^c is here fixedly connected with mutilated wheel 22^c and journaled to rotate loosely on platen arbor 5 therewith, as an assembled unit. The toothed driver 16^c is also placed on said arbor, but it is caused to have unison rotation therewith, conveniently through a key 17^c working in an axial slot in the hub of said driver. The driver is thus permitted to move axially on the platen arbor, but not angularly. A casing or collar 19^c, conveniently held in fixed lateral position on said arbor by means of key-pin 19^d, presses centrally upon laterally acting spring 18^c. Over the hub portion of wheel 16^c, and spring-pressed axially against said wheel by said spring, is placed a plate 18^d, said wheel in turn thus being pressed through wheel 22^c against member 6, thereby causing said member to be pressed into a frictional connection with the end of the platen, 4. A shouldered pin or axle 24^c on carriage-frame 2^c projects through an opening in said plate 18^d. Journaled on said axle is an assembled connecting gear composed of toothed wheels 25' and 25^d having unison rotation, one thereof meshing with wheel 22^c and one with driver 16^c. Member 6^c is preferably given the form of a drum containing within its contour most of the parts described, and having a face portion or wall supplied with two projections moving in different paths, the one being the detent 14^c and the other the pin 47 screwed into one of the threaded holes 47'.

An upstanding portion of carriage-frame 40 2^c bears a laterally extending axle 34^c upon which is journaled sleeve 43^c, said sleeve bearing a fixedly attached butt portion of paper-feeler 28^c and a fixedly attached weight 42^c. Said paper-feeler has a path 45 into a slot in paper-table 3 indicated at 33^c, said weight acting to hold it against the platen and retracted from said slot. The paper-feeler is knuckle-jointed at 75, a lug 76 on the lower portion thereof bearing 50 against the upper portion so as to limit movement of the lower portion in one direction, for backing-up purposes. Journaled loosely on sleeve 43^c and projecting into the path of detent 14^c on member 6^c is 55 a stop 15^c, a rearwardly extending lug thereon, 77, engaging with a position-stop 78 on weight 42^c so as to hold said stop 15^c in position for engagement by said detent. Detent 14^c can thus be backed-up past stop 15^c, 60 lug 77 separating from pin 78 and permitting the movement, and stop 15^c returning into operative position by its own weight. The sheet is entered. Projection 14^c eventually meets stop 15^c, and through the intermediate parts actuates paper-feeler 28^c to-

ward the paper-table, where it is detained by the sheet over slot 33^c, stop 15^c being thereby detained in the path of said detent 14^c and member 6^c detained by said detent in starting position. The passing of the 70 bottom end of the sheet from under the paper-feeler then releases member 6^c from detention, it is rotated frictionally until the toothed portion of mutilated wheel 22^c meshes with driver-actuated wheel 25', and 75 thereafter it is actuated positively to rotate with the platen. By the use of a gear arrangement increasing the speed of the member relatively to that of the platen I am able to bring a larger indicating surface 80 into indicating position with each advance of the sheet, so as to use larger indices. The indices employed will be as desired; I prefer to use downward-counting numerals to indicate the distances to the bottom end of 85 the sheet, or to a point on the sheet a given distance therefrom, such as are illustrated in Fig. 12.

It is to be noted that the indicating devices described in connection with Figs. 1 to 3 90 are intended to be used with all of the embodiments herein described, at will.

The devices shown in the drawings and described herein are part of a series of closely related inventions or improvements 95 which are presented in a number of co-pending applications for Letters Patent filed by me. The said devices have a number of general objects in common with those forming the subject-matter of different applications in the said series, and to a certain extent embody and utilize various principles and features which are common to devices shown and described in one or another of the said applications. Some of the said 105 common principles and features are claimed broadly in Letters Patent No. 1,053,919 granted upon my application filed April 20, 1908, aforesaid, and in Letters Patent No. 1,053,920, granted upon my application 110 filed March 30, 1912, Serial No. 687,463; Letters Patent No. 1,053,922, granted upon my application filed Dec. 15, 1909, Serial No. 533,309; Letters Patent No. 1,053,924, granted upon my application filed Dec. 15, 115 1909, Serial No. 533,355; Letters Patent No. 1,053,925, granted upon my application filed April 25, 1910, Serial No. 557,330; Letters Patent No. 1,053,926, granted upon my application filed April 4, 1912, Serial No. 120 688,358; Letters Patent No. 1,053,928, granted upon my application filed April 9, 1912, Serial No. 689,560, and Letters Patent No. 1,087,045, granted upon my application filed April 30, 1909, Serial No. 493,193; and 125 in my application filed Dec. 17, 1909, Serial No. 533,725; December 20, 1909, Serial No. 534,048, and December 5, 1912, Serial No. 735,107.

The branch of the general invention that 130

is covered hereby is distinguished by the characteristic features specified in the following claims:

I claim as new and desire to secure by Letters Patent,

5. 1. In a typewriting machine, in combination, a platen for advancing the sheet, indicating means, and paper-feeler means connected to call said indicating means into operation under the control of the leading end of the sheet. 70
10. 2. In a typewriting machine, in combination, a platen, a series of indices, and means under the control of the leading end of the sheet for bringing said indices into indicating prominence coördinately with the arrival of said leading end at predetermined distances from the printing point. 75
15. 3. In a typewriting machine, in combination, a platen, an operative member, indicating means called into operation through said member, means for giving said member a predetermined constant starting position, and means for giving said member movement coördinate with that of the platen from such position under the control of the leading end of the sheet and at a predetermined point in the progress of said leading end. 80
20. 4. In a typewriting machine, in combination, a platen, an operative member, indices called into operation through said member, means for giving said member a constant starting position, and means for giving said member movement coördinate with that of the platen from such position under the control of the leading end of the sheet. 85
25. 5. In a typewriting machine, in combination, a platen, an operative member, visual signaling means called into operation through said member, means for giving said member a constant starting position, and means for giving said member movement coördinate with that of the sheet from such position under the control of the leading end of the sheet. 90
30. 6. In a typewriting machine, in combination, a platen, an operative member, audible signaling means called into operation through said member, means for giving said member a predetermined starting position, and means for giving said member movement coördinate with that of the platen from such position under the control of the leading end of the sheet. 95
35. 7. In combination, typewriting mechanism including a platen, an operative member, means called into operation through said member for rendering a part or parts of the typewriter mechanism inoperative for use, means for giving said member a constant starting position, and means for giving said member movement coördinate with that of the sheet from such position under the control of the leading end of the sheet. 100
40. 8. In a typewriting machine, in combination, a carriage, a platen thereon, an operative member actuated from the platen, the main frame, printing instrumentalities thereon, means called into operation through said member for locking said printing instrumentalities against use in printing, and paper-feeler means for controlling the movement of said member under the control of the leading end of the sheet. 105
45. 9. In a typewriting machine, in combination, a platen, an operative member actuated to move in correlation with the platen, indicating means called into operation through said member, and a detent under the control of the leading end of the sheet connected to detain said member in starting position. 110
50. 10. In a typewriting machine, in combination, a platen, an operative member having a projection in connection therewith and having actuation from the platen, means controlled by the leading end of the sheet for controlling the movement of said member through said projection, and indicating means called into operation through said operative member. 115
55. 11. In combination, typewriting machine parts including a platen, an operative member, indicating means called into operation through said member, coöperating devices between said member and the platen for actuating said member, and means operated by a typewriting machine part under the control of the sheet for controlling the engagement of said actuating devices. 120
60. 12. In a typewriting machine, in combination, a platen, an operative member, indicating means called into operation through said member, operating devices for giving said member movement with the platen, and means operated from the platen under the control of the sheet for controlling the operation of said member by said devices. 125
65. 13. In combination, typewriting machine parts including a platen, an operative member, indicating means called into operation through said member, means for giving said member a predetermined starting position, toothed gearing between said member and the platen, and means operated by a typewriting machine part under the control of the sheet for causing said toothed gearing to engage and give said member movement with the platen. 130
70. 14. In a typewriting machine, in combination, a platen, an operative member, indicating means called into operation through said member, means for giving said member a predetermined starting position, toothed gearing, and means actuated from the platen for causing said toothed gearing to engage at the predetermined time and give said member simultaneous movement with the platen.
75. 15. In a typewriting machine, in combina-

- tion, a platen, an operative member, indicating means called into operation through said member, coöperating actuating devices for operating said member from the platen, 5 a paper-feeler, and toothed means under the control of said paper-feeler for calling said actuating devices into engagement at the predetermined time.
16. In a typewriting machine, in combination, a platen, an operative member, indicating means called into operation through said member, coöperating actuating devices for operating said member from the platen, a paper-feeler, and frictional means under 10 the control of said paper-feeler for causing said actuating devices to engage at the predetermined time and give said member working movement.
17. In a typewriting machine, in combination, a platen, an operative member, indicating means called into operation through said member, means for giving said member a predetermined starting position, toothed gearing, and sheet-controlled frictional 15 means for causing said toothed gearing to engage at the predetermined time and give said member simultaneous movement with the platen.
18. In a typewriting machine, in combination, a platen, an operative member, indicating means called into operation through said member, means including a toothed wheel and a coöperating mutilated gear for actuating said member from the platen, 20 frictional means for causing said toothed wheels to pass into mesh, and means including a movable stop for detaining said member in initial position and said toothed wheels out of mesh.
19. In a typewriting machine, in combination, a platen, an operative member, indicating means called into operation through said member, means including a toothed wheel and a coöperating mutilated gear for 25 actuating said member from the platen, a friction-drive device for causing said wheels to pass into mesh, and a sheet-controlled detent for detaining said member in predetermined position and said toothed 30 wheels out of mesh.
20. In a typewriting machine, in combination, a platen, an operative member, indicating means called into operation through said member, means for giving said member movement simultaneous with that of the platen but permitting detention thereof independently of the platen, and means for controlling the said movement, said controlling means including a detent element 35 constructed to detain said operative member from movement in either direction.
21. In a typewriting machine, in combination, a platen, an operative member actuated to move with the platen, indicating means 40 called into operation through said member, and controlling means for said member, including coöperating detent elements one of which is constructed with a recess and the other of which is constructed to enter said recess.
22. In a typewriting machine, in combination, a platen, an operative member actuated from the platen, indicating means called into operation through said member, and means for controlling the movement of said member, including detent elements one of which is constructed having recess walls of unequal height and one of which is adapted to enter between said recess walls.
23. In combination, typewriting machine parts including a platen, an operative member actuated from the platen, indicating means called into operation through said member, a stop connected to control said member, and a device operated from a typewriting machine part under the control of the sheet for controlling said stop.
24. In a typewriting machine, in combination, a platen, an operative member, indicating means called into operation through said member, means for giving said member simultaneous movement with the platen, a stop connected to control said movement, and a device actuated from the platen for operating said stop.
25. In a typewriting machine, in combination, a platen, an operative member actuated to move with the platen, indicating means called into operation through said member, coöperating detent elements one of which acts through the other to detain said member, and a sheet-controlled platen-actuated device for moving one of said detent elements out of engaging position with respect to the other.
26. In a typewriting machine, in combination, a platen, an operative member actuated from the platen, indicating means called into operation through said member, coöperating detent elements one of which acts through the other to detain said member, a toothed wheel having unison rotation with the platen, and a toothed member operated by said toothed wheel under the control of the sheet for moving one of said detent elements out of engaging position with respect to the other.
27. In a typewriting machine, in combination, a platen, a reciprocating paper-feeler having a sheet-controlled position, a device operated from the platen for retracting said paper-feeler from the sheet to facilitate moving the sheet, and indicating means controlled by said paper-feeler.
28. In a typewriting machine, in combination, a platen, a paper-feeler, a device operated from the forwardly-moving platen for retracting said paper-feeler from contact with the sheet, an operative member actuated from the platen under the control of

said paper-feeler, and indicating means called into operation through said member.

29. In a typewriting machine, in combination, a platen, an operative member actuated from the platen, indicating means called into operation through said member, a stop connected to control said member, a paper-feeler connected to control said stop, and a device operated from the platen for retracting said paper-feeler from contact with the sheet, to facilitate moving the sheet.

30. In combination, typewriting machine parts including a platen, a cam and cam follower, caused to operatively interact by a typewriting machine part, a paper-feeler moved away from the controlling work-sheet by said cam elements, and indicating means controlled by said paper-feeler.

31. In combination, typewriting machine parts including a platen, a cam and cam-follower, caused to operatively interact by an operated part of said mechanism, a paper-feeler moved away from the work-sheet by said cam elements, an operative member actuated from the platen under the control of said paper-feeler, and indicating means called into operation through said member.

32. In a typewriting machine, in combina-

tion, a platen, a paper-feeler, a cam operated from the platen for retracting said paper-feeler from contact with the work-sheet to facilitate moving the sheet, and indicating means controlled by said paper-feeler.

33. In a typewriting machine, in combination, a platen, a paper-feeler, a cam operated from the platen for retracting said paper-feeler from the work-sheet, an operative member, means for giving said member a constant starting position, and means under the control of said paper-feeler for giving said member movement to coördinate with that of the platen from such position.

34. In a typewriting machine, in combination, a platen, an operative member actuated to move with the platen, indicating means called into operation through said member, a stop connected to control said member, and a cam-retracted paper-feeler in control of said stop.

In testimony whereof I affix my signature in presence of two witnesses.

WILLIAM J. NEIDIG.
